UNITED STATES PATENT OFFICE.

A. B. HENDRYX, OF SEYMOUR, AND FRANKLIN FARREL, OF ANSONIA,
CONNECTICUT.

IMPROVEMENT IN MACHINES FOR TURNING IRREGULAR FORMS.

Specification forming part of Letters Patent No. 36,093, dated August 5, 1862.

To all whom it may concern:

Be it known that we, A. B. HENDRYX, of Seymour, in the county of New Haven and State of Connecticut, and FRANKLIN FARRELL, of Ansonia, in the same county and State, have invented a new and Improved Machine for Turning Irregular Forms, the same being more especially designed for turning the necks of bayonets; and we do hereby declare that the following is a full, clear, and exact description of the same, reference being had to the accompanying drawings, making a part of this specification, in which—

Figure 1 is a side sectional view of our invention, taken in the line *xx*, Fig. 3; Fig. 2, a plan or top view of the same; Fig. 3, a transverse vertical section of the same, taken in the line *yy*, Fig. 1; Fig. 4, a detached view of a bayonet.

Similar letters of reference indicate corresponding parts in the several figures.

This invention consists in the employment or use of a rotary adjustable cutter, a sliding pattern, and a movable stock or bed piece arranged in such a manner that articles having curved surfaces in their longitudinal profiles, or straight and curved surfaces combined, may be expeditiously turned in a perfect manner.

To enable those skilled in the art to fully understand and construct our invention, we will proceed to describe it.

A represents the bed of the lathe or machine, having a stationary head, *B*, secured upon it, in which a hollow shaft, *C*, is fitted, having a series of driving-pulleys, *D*, of different diameters, attached to it.

Within the hollow shaft *C* there is placed a bar or lever, *E*, which works on a fulcrum-pin, *a*. One end of this bar or lever has a curved arm, *F*, attached to it, through which a set-screw, *b*, passes, and the opposite end has a bent arm, *G*, attached, which carries a cutter, *H*, said cutter being secured in the end of a stock, *c*, attached to the end of the arm *G* by a pivot, *d*, and bearing, when at work, against a stop, *e*, at the end of the arm. The form or shape of the two arms *F G* is shown clearly in Fig. 1.

I is an upright permanently attached to the bed *A*, and having a tube, *J*, fitted permanently in its upper end, said tube having a slot, *f*, in its upper surface, extending its whole length,

and *K* is a screw which is fitted in the tube *J* and allowed to slide freely therein. On the tube *J* there is placed a pattern, *L*, which is allowed to slide on said tube, and is connected to the screw *K* by a pin or screw, *g*, which passes through the slot *f* in the tube *J*, as shown clearly in Fig. 1. On the screw *K* there is fitted a pulley, *L'*, having an internal screw-thread, into which the thread of the screw *K* fits.

M is a shaft which is fitted longitudinally in the bed *A*, and has a screw, *g*, cut on one part of it. This shaft is rotated by a belt, *h*, from the hollow shaft *C*, and the pulley *L'* is rotated by a belt, *i*, from shaft *M*. (See Fig. 1.)

N is a slide which is placed upon the bed *A*, and has a circular plate, *O*, fitted upon it. The plate *O* is provided with a pendent shaft, *P*, which passes loosely through a sleeve, *Q*, attached to the slide *N*. The shaft *P* has a shoulder, *j*, on it, which projects a trifle below the sleeve *Q*, and against which a collar, *R*, bears, said collar having a worm-wheel, *S*, at its lower end, which gears into the screw *g* on shaft *M*. The washer and nut are secured on shaft *P* by a nut, *T*. (See Figs. 1 and 3.)

The operation is as follows: In operating upon bayonets, the latter are secured one at a time to a support, *U*, on the plate *O*, the neck *k* of the bayonet (shown in red in Figs. 1 and 2) being secured in such a relative position with the cutter *H* that the latter may rotate around it as the shaft *C* is rotated. As the cutter rotates, the slide *N* is moved or fed along toward the head *B* in consequence of the screw *g* gearing into the worm-wheel *S* on shaft *P*, the nut *T* being screwed up, so as to cause the collar *R* to press or bind firmly against the shoulder *j* on the shaft *P*. During this straight or rectilinear movement of the slide *N* the cutter *H* turns the straight portion of the neck *k* of the bayonet, which is included between the socket *l* and the curve *m*. When the cutter reaches the curve *m*, the slide *N* comes in contact with stops *n* (one or more) on the bed *A*, and the movement of the slide is stopped, and the shaft *P*, plate *O*, and support *U*, with the bayonet, are rotated so that the cutter will turn the curved part *m* of the neck, which is a portion of a circle. At the commencement of the operation the nut *T* is screwed up suf-

ficiently far to cause the collar R to bind against the shoulder *j* of the shaft P to cause friction enough to prevent the plate O being turned under the action of the screw *g*; but when the movement of the slide N is stopped the plate O, it will be seen, must rotate, the friction of the collar R against the shoulder *j* being overcome. The concave form of the neck *k* is produced by the pattern L, which is moved along on the tube J by the action of the nut-pulley L' and screw K, the pattern as it moves actuating the set-screw *b*, and consequently the bar or lever E, which causes the cutter H to move inward or outward from the work, cutting the latter of the desired form circumferentially, in accordance with the pattern L. Thus it will be seen that the work is performed automatically, there being no manipulation required on the part of the attendant after the work is secured to the support U and the driving power applied to the pulleys D.

We would remark that the speed of the movement of the pattern L, as well as the speed of the rotation of the screw *g*, and also the pitch of the latter, are regulated so as to be proportionate to the speed of the rotation of the cutter H; and we would further remark that the cutter H is attached to the pivoted stock c in order to admit of the cutter turning

backward, when necessary, without marring the work.

We do not claim, broadly, the turning of irregular forms through the medium of a pattern acting upon a cutter, for patterns have been employed and arranged in various ways;

Having thus described our invention, what we do claim as new, and desire to secure by Letters Patent, is—

1. The rotary cutter H, attached to the bar or lever E, secured in the hollow shaft C of the driving-pulleys D, in combination with the sliding pattern L and sliding and rotating stock V, arranged substantially as and for the purpose herein set forth.

2. The particular arrangement of the slide N, plate O, with the stock V attached, and shaft P, together with the collar R, wormed wheel S, and nut T on shaft P, and the sleeve Q, attached to slide N, with the stop *n* on the bed A, for the purpose of admitting or producing the two movements of the support U, as set forth.

A. B. HENDRYX.
FRANKLIN FARREL.
